UNITED STATES PATENT OFFICE

WILLIAM B. JASPERT, OF SWISSVALE, PENNSYLVANIA, ASSIGNOR TO WESTINGHOUSE ELECTRIC & MANUFACTURING COMPANY, A CORPORATION OF PENNSYLVANIA

TRANSMISSION FOR EARTH-BOARING MACHINES

Application filed October 21, 1924. Serial No. 745,039.

My invention relates to transmission systems and more particularly to transmission mechanism utilized in the operation of earth boring machines.

- 5 It is among the objects of my invention to provide a transmission system for earth boring machines which shall be of simple compact and durable mechanical construction.
- 10 Another object of my invention is to provide a transmission system embodying a differential gear which shall have simple and improved regulating means for differentiating the speeds and directions of rotation
- 15 of its rotating elements.

Another object of my invention is to provide a drive mechanism of the above-designated character which shall be especially applicable to the drive mechanism of earth 20 boring machines in that it provides simple connecting means between the rotary drill table and the draw works and which shall have regulating means associated therewith for co-ordinating the function of the driven 25 elements.

Various types of earth boring devices have been heretofore proposed utilizing a differential gear intermediate the prime mover and the driven elements most of which utilize a 30 plurality of motors, one of which has a primary function of rotating the drill and an auxiliary function of regulating the direction of rotation and the rate of feeding the drill by means of the draw works through the 35 differential system.

My present invention is directed to a transmission system which is adapted to be utilized in connection with the drive mechanism of earth boring machines that embodies a 40 single motive device or motor and mechanical means for regulating the function of the draw works through the differential system.

My device is designed to provide a positive drive to the rotary table which is highly 45 desirable in controlling the torque and speed of the drill member. The draw works such as the hoist drum which cooperates with the drill member to feed the same by lowering it in the direction of the work is connected 50 through a differential gear mechanism to the

motor. I further provide an automatic control means for the differential to provide suitable regulation for the draw works in accordance with the load variations of the driving motor.

55 In the accompanying drawings constituting a part hereof and in which like reference characters designate like parts, the single figure is a diagrammatic view of a transmission system embodying the principles of my invention.

The system therein illustrated comprises a rotary drill table 1 having a rectangular opening 2 located centrally therein which is adapted to receive a similarly shaped portion 65 of a drill stem. The table is operatively connected by a bevel gear 3 to a drive shaft 4 having a sprocket wheel 5 mounted thereon. A drum member 6 constituting a part of the standard draw works, utilized in rotary drilling, is journaled for rotation by the drum shaft 7, by the journal brackets 8 secured in the usual manner to the derrick. 70

75 The end of the drum shaft is provided with a sprocket wheel 9. The drum member 6 is provided with a cable 10 which extends to the center of the rotary table 1 for the purpose of lowering or raising the drill stem or casings.

A differential gear mechanism 11 comprising a planetary system 12, and a pair of sun gears 13 and 14 is disposed in suitable working alignment with the drill table and drum and is operatively engaged by a pinion member 15 to an electrical motor 16 which constitutes a motive device. The sun gears 13 and 14 are provided with extension sleeves on which a sprocket wheel 17 and a magnetic brake mechanism 18 are respectively mounted. The planetary system 12 is keyed to a 90 drive shaft 19 which is provided with a sprocket wheel 20. The sprockets 9 and 17 of the drum and differential and the sprockets 5 and 20 of the rotary table and shaft 19 are respectively connected by sprocket chains 95 21. The magnetic brake 18 is connected to the windings of the motor 16 by suitable leads 22 and is of the type illustrated in detail and described in my copending application Serial Number 745,038 filed Oct. 21, 1924. 100

The operation of my device is briefly as follows: Assuming the drill stem to be operatively mounted in the rotary table 1 and connected to the cable 10 of the drum 6 with the rotary and drum shafts 4 and 7 respectively connected to the drive shafts 19 and 13 of the differential, then by actuating the drive motor 16 the shaft 19 will rotate and the rotary table 1 will revolve, thus turning the drill member. When the magnetic brake mechanism 18 is in its de-energized position, the sun gear 14 is free to rotate on the shaft 19 and the sun gear 13 by virtue of its sprocket gear connection to the drum member will rotate in the direction in which the drum is rotating to feed the cable in the direction of the work. The normal direction of rotation will therefore be counter-clockwise when looking in the direction of the planetary system from the sprocket wheel 17; and the sun gear 14 will revolve in the opposite direction while the planetary system 12 will rotate in a clockwise direction and in the same direction as the sun gear 14. As long as the sun gear 14 is free to rotate there will be no transmission of power to the sun gear 13. However, when the freedom of motion of the sun gear 14 is restrained, torque will be transmitted to the teeth of the sun gear 13 against the normal direction of operation to reverse the gear 13, thereby rotating the drum 6 in the opposite direction to hoist the cable 10, thus raising the drill away from the work. This function is effected through the magnetic brake 18, which is electrically connected to the windings of motor 16, so that when the torque of the motor varies with the load on the drill stem, the brake will become energized in varying degrees or de-energized to engage or release the sun gear 14. For instance, if the drill member is working through a relatively soft formation of shale or sand and suddenly encounters a conglomerate of boulders or hard rock, the increased load on the drill will react on the motor 16 and the magnetic brake 18 will operate, responsive to the load variation of the motor, resulting in a gripping of the sun gear 14 to retard its motion or entirely interrupt it. The continued rotation of the motor 16, though perhaps slower than its normal rotation, will in an extreme case, cause a reversal of the sun gear 13, thereby reversing the direction of the drum 6, which will lift the weight of the drill member or entirely remove it from the work, with the result that the load is released and the drill immediately comes up to its normal cutting speed. The magnetic brake 18 automatically becomes relatively de-energized and releases the sun gear 14, which permits the drum to again feed the drill in the advance direction; and normal operating conditions are thereby again established. The brake mechanism

18 may be independently energized from the line circuit 23, so that the sun gear 14 may be held stationary irrespective of the torque of the motor for the purpose of operating the drum member 6 for hoisting or auxiliary operations when the drill table 1 is idle. 70

It is evident from the foregoing description of my invention that a transmission system embodying the above principles will provide simple and efficient means for conducting the various operations essential to earth boring and that by the association of the magnetic control or regulating means a positive and sensitive regulating of the feeder mechanism is obtained. 75

Although I have described a specific embodiment of my invention it will be obvious to those skilled in the art that various modifications may be made in the details of construction, the size and proportion of the several cooperating parts and the application of my device without departing from the principles herein set forth. 85

I claim as my invention:

1. In an earth-boring system, in combination, a rotary drill-table, a motor for operating the drill-table, power-transmission means interposed between the motor and the drill-table, a hoisting mechanism associated with the drill-table to control the boring operations, means connecting the hoisting mechanism with the power-transmission means, and braking means cooperative with the power-transmission means for controlling the operation of the hoisting mechanism, said braking means being energized by the motor current. 90

2. In an earth-boring system, in combination, a rotary drill-table, a motor for operating the drill-table, a differential transmission interposed between the motor and the drill-table, a hoisting mechanism disposed to be driven by the motor through the differential transmission, and an electrically controlled brake cooperating with the differential transmission to vary the amount of power transmitted to the hoisting mechanism during the drilling operations, said brake being responsive, in operation, to the load current of the motor. 95

In testimony whereof, I have hereunto subscribed my name this 16th day of October, 1924.

WILLIAM B. JASPERT.
